UNITED STATES PATENT OFFICE.

HENRY HERRING, OF KOUTS, INDIANA.

DIPPER OR BUCKET.

1,296,800.

Specification of Letters Patent. Patented Mar. 11, 1919.

Application filed June 22, 1918. Serial No. 241,412.

To all whom it may concern:

Be it known that I, HENRY HERRING, a citizen of the United States, residing at Kouts, in the county of Porter and State of Indiana, have invented certain new and useful Improvements in Dippers or Buckets, of which the following is a specification.

This invention relates to improvements in what may be termed dippers or buckets 10 of the type especially designed for loading purposes.

The invention has for its object, among other things, to render the implement highly efficient and expeditious in action and to 15 enable it to perform its work with facility and satisfaction.

A further object of the invention is to provide for carrying out the aforesaid ends in a simple and inexpensive manner and in 20 highly satisfactory manner.

With these and other objects in view, the invention consists of certain instrumentalities and features of construction substantially as hereinafter more fully disclosed 25 and defined by the appended claims.

In the accompanying drawings is illustrated the preferred embodiment of my invention wherein it will be understood that various changes and modifications may be 30 made as to the detailed construction and arrangement of parts without departing from the spirit or scope of the claims, and in which drawings:

Figure 1 is a side elevation of my invention as when positioned for loading;

Fig. 2 is also a similar view showing the device in its unloading or discharging position;

Fig. 3 is an enlarged fragmental view 40 showing the parts in locked position;

Fig. 4 is a sectional view taken on the line 4—4 of Fig. 3;

Fig. 5 is a sectional view taken on the line 5—5 of Fig. 3; and

Fig. 6 is a fragmental detailed view showing more particularly the roll-pivot receiving slotted opening in a swinging bar member for said pivot, and a curved form of bar member.

In carrying out my invention I provide 50 a suitable bucket or dipper 1, of any preferred construction as shown or otherwise it being in the present instance of general rectangular form, and adapted to be loaded 55 through an oblong opening 2 provided in one of its sides. The bucket or dipper 1 is

suspended between the branches or prongs of a bifurcated bar or bail 3 said branches being pivoted to opposite sides thereof and retained vertically when the bucket or dipper 60 is in horizontal or filling position, by means of laterally projecting stops or lugs 4 on the bucket, said branches resting thereagainst as seen in Fig. 1. The bail or suspender 3 is extended upwardly and riveted 65 or otherwise secured to opposed spaced plates 5, and has pivoted to its upper end a pulley-and-block attachment 6, over the pulley of which is carried the lifting cable 7 which extends to a winding drum in the 70 cab distant therefrom, these however not being shown as they form no part of the invention and are commonly employed for a similar purpose.

Swingingly held by a pivot or bolt 8, intermediate the spaced plates 5 are opposed bars 9, which may be either straight as shown in Fig. 3, or curved as illustrated in Fig. 6, said pivot or bolt being passed through and secured to said plates, said 80 bars 9 themselves having riveted or bolted thereto as at 10, parallel angularly disposed arms 11 the function of which latter will be stated presently. The swing bars 9 have journaled therebetween, at their lower ends, 85 a roll 12, the journal for said roll being designated as 13 and suitably secured to the bars 9.

About in vertical alinement with, and a short distance below the roll 12, is a second, 90 small roll 14 which is mounted upon a journal 15 preferably in the form of a bolt suitably secured in the spaced plates 5, both the roll 12 and the roll 14 being suitably spaced by means of washers 16 from having 95 contact with the plates 5 as seen in Fig. 4.

The roll 12 has its journal held in slotted apertures, 17 the slots 17^a thereof opening out through the lower ends of the bars 9, as seen particularly in Fig. 6, and the 100 resultant split terminals of the plates 5 can be suitably manipulated to retain the roll in effective frictional or gripping action or engagement with the part interposed therebetween and the opposed roll 14 as will 105 be later appreciated.

Suitably secured to the normally upper side of the dipper are opposed upstanding spaced members 18^a, especially as shown in Figs. 2 and 5, and suitably attached or pivoted thereto, and therebetween, as by a vertical lateral bar 19 and a plurality of ad-

justing bolts 20, 21, 22 is an upwardly curved member or arm 23 resiliently held in operative position by a stout spring-member 24. The spring-member 24 is suitably secured in position at its base-end, as by a bolt 25, inserted through the parts 18^a and forcibly clamping down said base end, as seen in Fig. 3, the remaining portion of said spring 24 pressing against the rear edge portion 10 of the arm 23 holding the latter forcibly in normal position, and yet allowing for a limited rearwardly flexing action thereof. The bolts 21 and 22 are received by slots 25, 26 formed in the member or arm 23, and 15 are at right-angles to each other as relates to their axes as seen particularly in Fig. 3, to provide for the sundry adjustments of the arm as in correcting any variations arising from the shifting of the position of the arm.

20. In operation, it will be seen that, the dipper or bucket 1 occupying the position indicated in Fig. 1 for loading, it is suitably elevated, with its contents after loading, through the action of the cable 7 controlled 25 by the loading cable 27 winding on a drum located in a cab at a removed point, which are not herein shown. When the dipper or bucket is being loaded it is pulled toward the cab by the loading cable 27, which is connected by branch-members 28, 29 to the bucket 1 and the swinging or clamping bar 9, the branch member 28 being secured directly to the bucket, and the branch-member 29 to the swinging member 9 through the arm 35 11 as seen in Fig. 3. It will be understood, of course, that connection has been previously made between the arm 23 of the bucket 1 and the clamping rolls 12 and 14 of the bar 9 and member 5, respectively as seen in Fig. 40 3, the releasing action of which will be presently described. In further explanation of the loading operation, it is observed that when the bucket or dipper is full the operator releases the clutch (not shown) associated 45 with the loading cable 27 and puts a foot on a brake (not shown) which holds the loading cable taut, while the hoisting cable 7 raises the bucket sufficiently elevated to allow it to be swung to one side or the other. The 50 operator now releases the foot-brake, holding the loading cable, thus providing for the release of the lock formed by the rolls 12, 14 between which has been clamped the arm 23 of the bucket, and the consequent dumping 55 of the bucket or dipper. The bucket, perforce, now takes a vertical position and is swung back to be again loaded. As the bucket is lowered to assume a horizontal position upon the ground the upper curved end of the arm 23 as seen in Figs. 1 and 3 is received and automatically clamped between the rolls 12 and 14, ready for the repetition 60 of the above operation.

What I claim is:

65. 1. In apparatus of the character set forth,

the combination with a hoisting bucket member, of a supporting member connected thereto, a device to be secured carried by one member, and a clamping device carried by the other member and frictionally engaging 70 the device to be secured to hold the bucket member against dumping.

2. A device of the type described, including a bucket having an arm with an upwardly curved terminal, and a suspending 75 member provided with a swinging member having a clamping rotary element, said suspending member having a rotary clamping member co-operating with the aforesaid rotary member to receive and automatically 80 clamp therebetween said upper terminal of said arm, as the bucket takes its loading position.

3. A device of the type described, including a bucket having an upper end curved 85 arm, means for resiliently holding said arm in a predetermined position, and a suspending member having a pivoted member carrying a rotary clamping member, said suspending member being provided with a rotary 90 clamping member co-operating with the aforesaid rotary member to receive and automatically clamp therebetween said curved end of said arm.

4. A device of the type described, including a bucket having an arm provided with a curved upper end, and a suspending member provided with a swinging bar having a clamping rotary member at its lower terminal and below said clamping rotary member an angularly disposed arm, said suspending member having a clamping rotary member adapted to cooperate with the aforesaid clamping rotary member to provide for receiving and automatically clamping there- 100 between the upper curved end of said bucket-arm.

5. A device of the type described provided with a suspending bucket member said member having a swinging bar provided with a 110 clamping rotary member, a bucket with a curved arm, said suspending device having a clamping rotary member adapted for co-operation with the aforesaid clamping rotary member for automatically clamping the 115 upper end of the bucket arm.

6. A device of the type described, including a bucket having an arm provided with an upper curved end, said bucket being suspended from a bail, said bail having means 120 for the attachment thereto of hoisting means and means carrying a pivoted or swinging arm provided with a clamping member and a fixed angularly disposed arm, said swinging arm carrying means having a clamping 125 rotary member co-operating with the aforesaid rotary clamping member to receive and clamp automatically therebetween said bucket-arm.

7. In apparatus of the character set forth, 130

the combination with a hoisting bucket member, of a supporting member connected thereto, a device to be secured carried by one member, a clamping device carried by the other member and engaging the device to be secured to hold the bucket member against dumping, and bucket moving means connected to the clamping device to secure the effective action thereof.

10 8. In apparatus of the character set forth, the combination with a hoisting bucket mem-

ber, of a supporting bail member therefor, a device to be secured carried by one member, a friction clamping device carried by the other member and engaging the device to be secured, said friction clamping device including a pivoted arm, and bucket moving means connected to the arm for increasing the frictional engagement of the clamping device upon the securing device.

20

In testimony whereof I affix my signature.

HENRY HERRING.
